(57) **CLAIM**

The ornamental design for a toll transponder cover, substantially as shown and described.

DESCRIPTION

FIG. 1 is a top, and right side perspective view of the toll transponder cover showing same exploded from a typical toll transponder;

FIG. 2 is a front view of the toll transponder cover;

FIG. 3 is a rear view of the toll transponder cover;

FIG. 4 is a right side view of the toll transponder cover, the other side being the mirror image thereof; and,

FIG. 5 is a top view of the toll transponder cover, the bottom appearing the same as the top.

The broken-line disclosure of the toll transponder in FIG. 1 is for illustration purposes only and forms no part of the claimed design.
